Patented Oct. 22, 1968

212,499

COMBINED LAMP AND CLOCK

Jay Monroe, Great Neck, N.Y., assignor to Tensor Corporation, Brooklyn, N.Y., a corporation of New York

Filed Feb. 6, 1968, Ser. No. 10,466

Term of patent 14 years

(Cl. D48—20)

FIG. 4

FIG. 5

FIG. 6

FIGURE 1 is a perspective view of a combined lamp and clock showing my new design;

FIGURE 2 is a side elevational view thereof;

FIGURE 3 is a top plan view thereof;

FIGURE 4 is a front elevational view thereof;

FIGURE 5 is a rear elevational view thereof; and

FIGURE 6 is a perspective view of a further embodiment of a clock lamp, the undisclosed portion presents a similar appearance as that disclosed in FIGURES 1-5.

The dominant features of my design reside in the portions shown in full lines.

I claim:

The ornamental design for a combined lamp and clock, as shown and described.
